UNITED STATES PATENT OFFICE.

WILLIAM L. GRAY AND JOSEPH RIVERS, OF EVANSTON, WYOMING.

POP SAFETY-VALVE.

SPECIFICATION forming part of Letters Patent No. 487,029, dated November 29, 1892.

Application filed June 22, 1892. Serial No. 437,616. (No model.)

To all whom it may concern:

Be it known that we, WILLIAM L. GRAY and JOSEPH RIVERS, citizens of the United States, residing at Evanston, in the county of Uinta and State of Wyoming, have invented a new and useful Pop Safety-Valve, of which the following is a specification.

This invention relates to pop safety-valves; and it has for its object to provide an improved safety and exhaust valve adapted for use upon locomotives and stationary boilers, steam-chests, and any particular part of an engine designed to carry a given amount of steam-pressure.

15 The main and primary object of the invention is to provide an improved safety and exhaust valve of this character which will relieve the pressure of steam and accurately and evenly reduce the same, so that there will not only be no undue loss of steam, but the 20 operation of the valve will be attended with much less noise than those ordinarily in use.

With these and many other objects in view, which will readily appear as the nature of the 25 invention is better understood, the same consists in the novel construction, combination, and arrangement of parts hereinafter more fully described and claimed.

In the accompanying drawings, Figure 1 is 30 a side elevation of a safety and exhaust valve constructed in accordance with this invention. Fig. 2 is a vertical longitudinal sectional view of the same. Fig. 3 is a detail in perspective of the regulating ring, cap, or slide.

35 Referring to the accompanying drawings, A represents the valve body or casing, adapted to be secured to the boiler or valve-chest which is to be relieved of undue pressure therein, and said valve casing or body is provided with an exteriorly-threaded outer edge α and an interiorly-beveled valve-seat portion α' and an adjacent flat or horizontal valve-seat α^2 , leading from said beveled portion at the outer end of the body. The flat or horizontal 40 portion of the valve-seat is inclosed within the extreme outer exteriorly-threaded portion of the valve-casing, and intermediate of the said threaded portion and the lower valve-seat is formed an annular steam-groove B, the 45 outer wall of which is raised above the plane of the valve-seat, so that the steam escaping from beneath the valve-disk C will strike the

said outer wall and be directed straight up without spitting laterally from under the valve and filling the cab or engine-room with 55 the escaping steam. The valve-disk C is provided with a winged stem D, smaller than the diameter of the same and working snugly within the valve casing or body to evenly guide the valve in its movement. The said 60 valve-disk C is further provided with an annular groove E in its under face, which lies directly over the flat portion of the valve-seat, and on the inside of which is formed the beveled contact-face E', which is designed to 65 rest in the beveled portion of the valve-seat, while the outer edge of the groove fits flat upon the flat portion of the valve-seat, so as to form a double seat for the valve. The intermediate groove naturally forms a steam-cush- 70 ion for the valve, so that when the pressure of steam is reduced the valve settles gradually and quietly upon its seat without the usual attendant pop and jar. The said valve-disk C is further provided with an alternate 75 series of circular openings F, extending therethrough and opening into the annular groove E near its outer edge.

Adjustably mounted upon the valve-disk is the regulating ring-cap G, provided with an 80 alternate series of perforations H, which are designed to register with the openings F in the valve-disk, and are further provided with the circular slots I, through which pass the 85 adjusting-screws J, providing means for the circular adjustment of said rings, so as to open or close the openings or as many of such openings as desired, according to the needs of the engine with which the valve is used in connection. It will be readily seen that when 90 the openings in the valve-disks are closed by the ring-slide all of the steam must escape from under the valve-disk, and the same would therefore remain open longer and cause more pressure of steam to be lost in the boiler or 95 chest. By moving the ring-slide so as to uncover the said openings it will be readily seen that a great deal of the steam-pressure is taken off of the valve by the steam escaping directly therethrough, and thus allows the valve to 100 close much more quickly to keep a more even pressure in the boiler. A bridge or yoke K is provided with an interiorly-threaded ring K', engaging the exterior edge or end of the

valve body or casing, and is provided with an upper threaded perforation *k'*, standing directly over the center of the valve-disk inclosed within the same, and is designed to receive the adjusting-screw *L*. The adjusting-screw *L* bears upon the spring-follower *N*, resting upon the top of the valve-spring *M*, the lower end of which rests upon the spring-support *O*, having a pointed bearing-pin *P* bearing directly in the center of the valve-disk to place the spring-pressure evenly thereon. The tension of the spring may be adjusted so that the valve will open under any given pressure of steam.

15 The many advantages of the herein-described valve will readily suggest themselves to steam-engineers.

Having thus described our invention, what we claim, and desire to secure by Letters Patent, is—

20 The valve body or casing having an inner beveled and an adjacent horizontal valve-seat at one end thereof, an annular groove surrounding the flat valve-seat and having a raised outer wall extending above the plane of the same and an exteriorly-threaded portion, a winged valve working over the upper 25 end of the casing and having a beveled and unbeveled contact-face adapted to register

with the valve-seats, an annular cushioned groove on its under side directly over the horizontal portion of the valve-seat and a circular series of vertical steam-openings leading from the under cushion-groove, a circularly-adjustable ring-slide working on the valve and provided with a series of perforations adapted to cover and uncover the steam-openings in the valve, and adjusting-slots, adjustment-screws passing through said slots into the valve, a bridge or yoke having an interiorly-threaded ring engaging the threaded portion of the valve-body and an upper threaded perforation, a spring-support having a pointed bearing-pin resting on the center of the valve, a spring arranged on said support, a follower-block mounted on the upper end of the spring, and an adjusting-screw passing through said upper threaded perforation and bearing on said block, substantially as set forth.

50 In testimony that we claim the foregoing as our own we have hereto affixed our signatures in the presence of two witnesses.

WILLIAM L. GRAY.
JOSEPH RIVERS.
